METHOD AND APPARATUS FOR
DRIVING PILES

Chester A. Orr and Edmund W. Riemenschneider,
Canton, Ohio, assignors to The Union Metal
Manufacturing Company, Canton, Ohio, a cor-
poration of Ohio

Application March 1, 1934, Serial No. 713,535

18 Claims. (Cl. 61—57)

The invention relates to piles and more particularly to the driving and setting of piles in which a tapered, tubular, metal shell is sunk into the ground by utilizing a tapered, substantially rigid, driving mandrel or core for driving the shell into the ground, after which the core is removed and the shell may be filled with suitable bearing material, preferably concrete, to form the pile; and the present invention is a continuation in part of the common subject matter of our copending application for Piles and methods and apparatus for setting the same, filed October 12, 1932, Serial No. 637,454.

A tapered, tubular, metal shell of almost any length, preferably provided with a nose integral with the small lower end thereof, may be sunk to almost any depth into the ground by utilizing a tapered, substantially rigid, longitudinally continuous, driving mandrel, by providing the shell with longitudinal ribs, corrugations or flutes, by telescoping the mandrel within the shell and engaging the mandrel with the shell flutes and nose, and by then driving the mandrel to drive the shell into the ground. The mandrel may then be readily removed from the shell, and the tapered shell which is preferably, but not necessarily, formed of very thin sheet metal, provides a form which may be filled with a core of suitable material, such as concrete, to form a pile.

It is therefore the principal object of the present invention to provide a tapered, tubular, metal shell having a cap or nose on its small end, to provide a tapered, substantially rigid, longitudinally continuous, driving mandrel, to provide the shell with longitudinal ribs, corrugations or flutes, to telescope the mandrel within the shell in line contact with the ribs, corrugations or flutes and in engagement with the shell nose, to drive the mandrel and shell into the ground to the desired depths, to then remove the mandrel, and to then preferably fill the shell with a core of suitable material, such as concrete, to form a pile.

We have discovered, that if a longitudinally ribbed, corrugated or fluted, tapered, tubular metal shell is driven into the ground by a slightly larger tapered, substantially rigid, driving mandrel, that initially the mandrel is telescopically wedged into the shell and radially expands the shell substantially throughout its length until the lower end of the mandrel engages the shell nose, thereby establishing contact by the mandrel with all of the shell flutes throughout their entire length; with the result that the driving force thereafter imparted to the mandrel is uniform-

ly transmitted to the shell throughout the entire length of the shell, to drive the shell into the ground.

Thus, the difficulties which are encountered in utilizing a radially non-expansive shell, due to the shell and mandrel being off-taper with respect to one another, due to the mandrel being worn, due to the shell or mandrel being out of round, or due to the shell or mandrel being undersize or oversize, are avoided; and these difficulties, if not avoided, might result in a tearing or splitting of the shell, or in a tearing out of the nose thereof, or in an inefficient utilization of the driving force imparted to the mandrel.

It is therefore a further object of the present invention to provide for the driving of pile shells into the ground by utilizing a longitudinally ribbed, corrugated or fluted, tapered, tubular, metal shell, by utilizing a tapered, substantially rigid, driving mandrel, by telescoping and wedging the mandrel into the shell and radially expanding the shell throughout its entire length until the lower end of the mandrel engages the shell nose and/or until contact is established between the mandrel and all of the shell flutes throughout their entire length, by then driving the shell and mandrel into the ground, and by then removing the mandrel from the shell.

Furthermore, we have discovered that the driving of a tapered pile shell with a tapered mandrel by initially radially expanding the shell and thereafter driving the shell into the ground may best be accomplished when a longitudinally ribbed, corrugated or fluted, tapered, tubular metal shell is utilized. However, if a tapered shell is to be so driven, care must be taken to avoid the usual difficulty of removing the mandrel from the shell, which is experienced in driving tapered pile shells, because of a tendency of the shell to come up with the mandrel.

A number of prior methods or constructions have been proposed for overcoming the tendency of a pile shell to come up with the mandrel which has been used to drive the shell into the ground, which include among others, the utilization of collapsible and longitudinally sectional mandrel constructions. However, such mandrel constructions which have heretofore been used are objectionable because of the initial high cost of the same, because of the injury or wear to which the numerous interconnected parts are subjected by the blows of the pile driving hammer, and because of time lost in making repairs to such constructions. Still another mandrel construction avoids some of these difficulties, but frequently

causes pulling out or failure of the shell nose when the mandrel is being stripped from the shell.

We have discovered that if a substantially rigid, preferably longitudinally continuous, tapered, driving mandrel having a radially expansible and contractable, preferably longitudinally continuous, shell engaging member is utilized for driving a tapered, tubular, metal pile shell into the ground, an initial radial expansion of a shell whether or not it is longitudinally ribbed, corrugated or fluted, together with the attendant advantages thereof, may be obtained; and/or the mandrel may be readily removed from any type of tapered tubular pile shell driven by such a mandrel without in any manner dislodging the pile shell from its driven position in the ground, thereby overcoming the difficulties heretofore experienced in the use of prior mandrel constructions.

It is therefore a further object of the present invention to provide a tapered, substantially rigid, driving mandrel having an expansible and contractable shell engaging member for driving a tapered, tubular, metal pile shell into the ground, or for driving a tapered, longitudinally ribbed, corrugated or fluted, tubular, metal pile shell into the ground.

These and other objects may be obtained by the elements, combinations, structures, methods and apparatus, preferred embodiments or steps of which are hereinafter claimed, and described in detail, and are likewise shown in the drawings, in which:

35 Figure 1 is a diagrammatic view, partly in section, showing the improved pile driving apparatus with the improved mandrel inserted in a longitudinally fluted, tapered pile shell, ready to radially expand the pile shell;

40 Fig. 2 is a view similar to Fig. 1, showing the pile shell driven to the desired position in the ground;

45 Fig. 3 is a view similar to Figs. 1 and 2 showing the position of the members of the improved mandrel after the mandrel driving member has been partially withdrawn from the mandrel sleeve member to permit contraction of the sleeve member;

50 Fig. 4 is a sectional view through the mandrel and shell taken on the line 4-4, Fig. 1;

Fig. 5 is a sectional view similar to Fig. 4, taken on the line 5-5, Fig. 2;

Fig. 6 is a sectional view similar to Figs. 4 and 5, taken on the line 6-6, Fig. 3;

55 Fig. 7 is an enlarged fragmentary view of certain of the parts shown in Fig. 4, also showing in dot-dash lines the position of the same parts as shown in Fig. 5;

Fig. 8 is a longitudinal sectional view of the 60 pile shell shown in Figs. 1 to 7, after it has been driven into the ground;

Fig. 9 is a longitudinal sectional view of the pile shell shown in Fig. 8 filled with concrete to form a pile;

65 Fig. 10 is a view similar to Fig. 4, but showing a slightly modified form of mandrel in which a solid driving member is utilized;

Fig. 11 is a view similar to Fig. 10, but showing the parts after the shell has been radially expanded;

Fig. 12 is a view similar to Fig. 4, but showing a modified form of shell in which inturned shell flutes are utilized;

Fig. 13 is a view of the parts shown in Fig. 12 75 after the shell has been radially expanded;

Fig. 14 is a view similar to Fig. 4, but showing another modified form of longitudinally corrugated pile shell;

Fig. 15 is a view of the parts shown in Fig. 14 after the corrugated shell has been radially expanded;

Fig. 16 is a view similar to Fig. 4 showing a still further modified form of longitudinally ribbed shell;

Fig. 17 is a view of the parts of Fig. 16 after the longitudinally ribbed shell has been radially expanded;

Fig. 18 is a view similar to Fig. 4, showing another modified form of shell;

Fig. 19 is a view similar to Fig. 4, showing still another modified form of shell; and

Fig. 20 is a view similar to Fig. 4, showing the improved mandrel used for driving a plain shell.

Similar numerals refer to similar parts throughout the drawings.

Referring to Figs. 1 and 4, a tapered, tubular pile shell is generally indicated at 18, and is preferably, but not necessarily, formed of light gauge sheet or strip metal, to provide, when driven into the ground, a form which may be 25 filled with a core of suitable material, such as concrete, to form a pile. The shell 18 is preferably provided, on its lower end, with a nose boot 19 and a nose cap 20; and the shell 18 is also 30 preferably provided with longitudinally continuous, preferably outturned reinforcing flutes 21. The shell 18 may be any desired length, and because of its taper, it readily penetrates the ground and may therefore be readily driven to the necessary depth.

35 A usual pile driver may be utilized for driving the shell into the ground, and the same may include the tower frame 22, a frame 23 slidably mounted in the tower frame and a hammer unit. The hammer unit comprises a steam cylinder 24 40 slidably mounted in the frame 23, a hammer base or core 25 suspended from the cylinder by the rods 26, and a reciprocable hammer plunger 27 guided for reciprocation on the rods 26 and connected with a piston in the cylinder 24 by a 45 piston rod 28.

The improved driving mandrel includes an inner, one-piece, tapered, substantially rigid, longitudinally continuous, preferably tubular, driving member 29, provided with a nose 30 and 50 connected with the hammer base 25 by a suitable sling 31; and the improved mandrel also includes an outer one-piece tapered, split-sleeve, resiliently expansible and contractable, longitudinally continuous, shell-contacting member 55 32 telescopically mounted for longitudinal movement on the inner member 29.

The split-sleeve member 32 is preferably provided at its upper end with a split-reinforcing-ring 33. Means is provided limiting longitudinal 60 movement of the outer mandrel member 32 on the inner mandrel member 29, as by providing a cross arm 34 which passes through the upper end of the split-sleeve member 32, at 35, and is secured thereto as by a pin 36 and a bolt 37. 65 The cross arm 34 is adapted to be reciprocated through the length of the cross arm slots 38 in the upper end of the inner mandrel member 29.

The cross arm 34 is also adapted to be connected to or to be engaged by the lower end of 70 the frame 23, as at 39, for the purpose of stripping the mandrel from the shell 18, as will be later described.

In the operation of driving a shell 18 in the ground, the frame 23 with its contained hammer 75

unit is raised to the top of the derrick tower with the improved mandrel projecting therefrom. The shell 18 is then placed under the mandrel and the mandrel is lowered to the position shown in Fig. 1, when the outer split-sleeve mandrel member 32 is telescoped within the shell 18, and the lower end of the outer mandrel member 32 rests on the shell nose cap 20.

The driving operation is then commenced by 10 operation of the steam cylinder 24 so that the operation of the hammer 27 drives the inner mandrel driving member 29 longitudinally telescopically into the outer split-sleeve mandrel member 32 until the nose 30 of the inner mandrel member 29 contacts with the nose cap 20 of the shell 18, and until the hammer base 25 contacts with the upper ring end 33 of the split-sleeve member 32. This driving operation radially expands the split-sleeve member 32 from the position 20 shown in Figs. 1, 4 and 7, to the position shown in Fig. 5 and shown in dot-dash lines in Fig. 7. The radial expansion of the split-sleeve member 32 causes a widening of the open slot indicated at 40 in Fig. 4, between the adjacent edges of the slit in the sleeve member 32 so that the open slot has a width as indicated at 40a in Figs. 2 and 5.

Meanwhile, the radial expansion of the split-sleeve member 32 causes a radial expansion of 30 the walls of the pile shell 18 because of the fact that the shell 18 is longitudinally corrugated; with the result that the corrugations 21 become slightly shallower as indicated at 21a in Fig. 5, and in dot-dash lines in Fig. 7. The radial expansion of the shell 18 is accompanied by the establishment of substantially complete contact by the mandrel with all of the shell flutes throughout their entire length, so that driving force thereafter imparted to the mandrel is uniformly 40 transmitted to the shell throughout the entire length of the shell.

The hammer 27 is then operated to drive the shell 18 and mandrel into the ground to the desired depth, as indicated in Fig. 2. Thereafter, 45 the mandrel is stripped from the shell by applying a pulling force to the cable 41, which, operating through the sheaves 42 and 43 applies an upward pull to the mandrel driving member 29 through the cylinder 24, the rods 26, the hammer base 25, and the sling 31; which upward pull reacts against the mandrel sleeve member 32 through the medium of the frame 23 and the cross arm 34. Thus, the upward pull on the cable 41 causes a relative stripping motion to be imparted to the mandrel members 29 and 32, whereby the inner driving member 29 is axially moved relative to and partially withdrawn from the sleeve or shell engaging member 32 until the 55 position of the parts shown in Figs. 3 and 6 is reached, so as to release the expanding pressure of the driving member 29 on the shell engaging member 32; whereupon the lower ends of the cross arm slots 38 of the inner mandrel member 29 engage the cross arm 34 and the mandrel members 29 and 32 are removed in unison from the shell 18.

As the mandrel driving member 29 is being 70 partially withdrawn from the resilient split-sleeve member 32, the split-sleeve member 32 may contract radially to the position shown in Figs. 3 and 6 of the drawings and engagement thereof with the shell 18 is thereby released so that the removal of the mandrel from the shell 75 18 does not pull the shell up; but the shell remains

in situ in the ground at the place or location to which it was driven.

Thereafter, other pile shells may be driven by the pile driver and mandrel; a pile shell 18 driven to the desired position in the ground being shown in Fig. 8. Subsequently, if desired, the pile shell 18 may be filled with suitable material such as concrete 42 to form a pile indicated at 43 in Fig. 9. It should be understood, however, that the pile shells 18 are not necessarily filled with concrete, but are only so filled in case they are made of thin gauge material. If the material from which the shell 18 is made, is a heavy gauge material, such a shell may be driven into the ground in the manner described above; and may thereafter serve directly as a pile, in the manner which may also be illustrated by Fig. 8.

While the improved driving mandrel has been described as preferably comprising a tubular inner driving member 29, it is understood that such 20 mandrel inner driving member may be a solid member, as shown in Figs. 10 and 11 at 29a; the parts being shown in Fig. 10 in the position which they assume when the mandrel is being inserted into the shell 18, and the parts being shown in Fig. 11 in the position which they assume after the mandrel has been fully telescopically wedged into the shell 18 to radially expand the shell.

Referring to Figs. 12 and 13, the shell 18a to be driven into the ground may be provided with 30 inturned longitudinal flutes 21' rather than out-turned flutes as shown in Figs. 1 to 10 inclusive; the parts being shown in Fig. 12 in the position which they assume when the mandrel is being inserted into the shell 18a, and the parts being shown in Fig. 13 in the position which they assume after the mandrel has been fully telescopically wedged into the shell 18a to radially expand the shell and provide shallower flutes 21a'.

Likewise, referring to Figs. 14 and 15, in certain 40 cases it may be desired to utilize a shell 18b, which is provided with longitudinal corrugations 21b; the parts being shown in Fig. 14 in the position which they assume when the mandrel is being inserted into the shell 18b, and the parts being shown in Fig. 15 at the position which they assume after the mandrel has been fully telescopically wedged into the shell 18b to radially expand the shell and provide shallower corrugations 21b'.

Likewise, the shell 18c shown in Figs. 16 and 17, 50 instead of being longitudinally fluted or longitudinally corrugated, may be provided with longitudinal ribs 21c; the parts being shown in Fig. 16 in the position which they assume when the mandrel is being inserted into the shell 18c, and the parts being shown in Fig. 17 in the position which they assume after the mandrel has been fully telescopically wedged into the shell 18c to radially expand the shell and form shallower ribs 21c'.

Referring to Fig. 18, there is shown therein another form of shell 18d provided with longitudinal panels 21d, which may be readily driven by the improved mandrel having the mandrel driving member 29 and the mandrel split-sleeve member 32; and referring to Fig. 19, there is shown therein another modified form of improved shell 18e provided with longitudinal panels 21e connected by out-turned longitudinal ribs 21e', which may also be readily driven by the improved mandrel 70 consisting of the mandrel driving member 29 and the mandrel split-sleeve member 32.

And finally, referring to Fig. 20, the improved mandrel comprising the mandrel driving member 29 and the mandrel split-sleeve member 32, may 75

be utilized for driving a plain, tapered pile shell 18f. The improved mandrel upon being initially inserted into the shell will accommodate the shell 18f even if the shell is slightly out of round, 5 or slightly off taper. Although there may be no considerable radial expansion of the shell 18f, excepting to a slight extent as by a stretching of the metal shell walls for accommodating an out of round or an off taper shell, or one which 10 otherwise does not match the mandrel; nevertheless, the use of the improved mandrel for driving a plain tapered shell 18f permits easy removal of the mandrel from the shell after the shell has been driven.

15 The terms "rigid" or "substantially rigid" or "solid" utilized herein as distinguished from "collapsible" or "longitudinally sectional", refer to mandrels having sufficient rigidity and strength to be driven into the ground and/or removed 20 therefrom without failing under normal working conditions; the terms "one-piece" or "integral" utilized herein with reference to mandrels, mandrel members or shells, refer to elements which may be originally made of a plurality of pieces 25 and permanently joined together in any suitable manner so that they may be driven or sunk into the ground as unitary structures; and finally, the terms "ribbed", "corrugated", "panelled", and "fluted" are used herein more or less synonymous- 30 ly, it being understood that in referring to a fluted shell, herein and in the claims, the same is intended to include shells which are either ribbed, corrugated, panelled or fluted, or are otherwise susceptible to being radially expanded.

35 We claim:—

1. A method of setting piles, including the steps of utilizing a tapered, fluted, tubular, metal shell; securing a nose to the small end of the shell; utilizing a substantially rigid, longitudinally continuous, tapered mandrel; pulling the shell into the ground by driving the mandrel against the nose while normally maintaining the mandrel within the shell in contact with the bases only of the flutes; removing the longitudinally continuous mandrel and leaving the shell in situ to form a pile shell; and filling the shell with a core.

2. A method of setting piles, including the steps of utilizing a tapered, tubular, metal shell having 50 outturned longitudinal flutes; utilizing a substantially rigid, longitudinally continuous, tapered mandrel; telescoping the mandrel within the shell and contacting the mandrel with the bases only of the outturned flutes; driving the mandrel and shell into the ground; removing the longitudinally continuous mandrel and leaving the shell in situ to form a pile shell; and filling the shell with a core.

3. A method of setting piles, including the steps 60 of utilizing a tapered, tubular, metal shell having outturned longitudinal flutes; securing a nose to the small end of the shell; utilizing a substantially rigid, longitudinally continuous, tapered mandrel; pulling the shell into the ground by driving the mandrel against the nose while normally maintaining the mandrel within the shell in contact with the bases of the outturned flutes; removing the longitudinally continuous mandrel and leaving the shell in situ to form a pile shell; 70 and filling the shell with a core.

4. A method of setting piles, including the steps of utilizing a tapered, tubular, metal shell having 75 inturned longitudinal flutes; securing a nose to the small end of the shell; utilizing a substantially rigid, longitudinally continuous, tapered

mandrel; pulling the shell into the ground by driving the mandrel against the nose while normally maintaining the mandrel within the shell in contact with the apexes of the inturned flutes; removing the longitudinally continuous mandrel and leaving the shell in situ to form a pile shell; and filling the shell with a core.

5. A method of driving a pile shell, including the steps of utilizing a tapered, fluted, tubular, metal shell; utilizing a substantially rigid, tapered, driving mandrel; radially expanding the shell throughout its length by driving and telescopically wedging the mandrel into the shell; then driving the shell and mandrel into the ground; and then removing the mandrel from the shell and leaving the shell in situ in the ground.

6. A method of driving a pile shell, including the steps of utilizing a tapered, fluted, tubular, metal shell; providing a nose on the small end of the shell; utilizing a substantially rigid, tapered, driving mandrel; radially expanding the shell throughout its length by telescoping and wedging the mandrel into the shell until contact is established between the mandrel and all of the shell flutes throughout their entire length, and until the lower end of the mandrel engages the shell nose; then driving the shell and mandrel into the ground; and then removing the mandrel from the shell and leaving the shell in situ in the ground.

7. A method of driving a pile shell, including the steps of utilizing a tapered, fluted, tubular, metal shell; utilizing a substantially rigid, tapered, driving mandrel having an expansible and contractable shell engaging member; driving and 35 telescopically wedging the mandrel into the shell to radially expand the shell engaging member into engagement with the shell and to thereafter radially expand the shell throughout its length; then driving the shell and mandrel into the 40 ground; and then removing the mandrel from the shell by first axially moving the driving mandrel relative to the shell engaging member to release the expanding pressure of the driving mandrel on the shell engaging member and thereafter withdrawing the mandrel and its shell-engaging member from the shell to leave the shell in situ in the ground.

8. A method of driving a pile shell, including the steps of utilizing a tapered, fluted, tubular, metal shell; providing a nose on the small end of the shell; utilizing a substantially rigid, tapered, driving mandrel having an expansible and contractable shell engaging member; driving and 50 telescopically wedging the mandrel into the shell to radially expand the shell engaging member into engagement with the shell and to thereafter radially expand the shell throughout its length until the lower end of the mandrel engages the shell nose; then driving the shell and mandrel 55 into the ground; and then removing the mandrel from the shell by first axially moving the driving mandrel relative to the shell engaging member to release the expanding pressure of the driving mandrel on the shell engaging member and thereafter withdrawing the mandrel and its shell engaging member from the shell to leave the shell in situ in the ground.

9. A pile shell driving mandrel, including a tapered, substantially rigid, longitudinally continuous, driving member; a tapered, split-sleeve, shell-contacting member telescoped over said driving member and mounted for longitudinal movement thereon; and means limiting longi- 70 75

- tudinal movement of said sleeve member on said driving member.
10. A pile shell driving mandrel, including a tapered, substantially rigid, longitudinally continuous, driving member; and a tapered, longitudinally continuous, expansible and contractable, split-sleeve, resilient, metal, shell-contacting member telescoped over said driving member; said sleeve and driving members being mounted 10 for limited relative longitudinal movement.
11. A pile shell driving mandrel, including an inner, tapered, substantially-rigid, driving member; and an outer, tapered, resiliently expansible and contractable, longitudinally continuous, 15 split-sleeve member mounted on the driving member.
12. A pile shell driving mandrel, including a one-piece, tapered, rigid, driving member; and a one-piece, tapered, resiliently expansible and 20 contractable, split-sleeve member mounted on the driving member.
13. Apparatus for driving pile shells, including a tapered, substantially rigid, driving mandrel adapted to be inserted in a pile shell, said mandrel having an inner, tapered, driving member and having an outer, tapered, resilient, split-sleeve member mounted on the driving member; means for telescoping the driving member within the sleeve member for radially expanding said 30 sleeve member to establish contact throughout the length thereof with the pile shell and for thereafter driving the shell into the ground; and means cooperating with said last mentioned means and the sleeve member and driving member for applying oppositely acting stripping forces to said mandrel sleeve member and said driving member and for thereafter removing said mandrel from the shell.
14. Apparatus for driving pile shells, including 40 a tapered, substantially rigid, driving mandrel adapted to be inserted in a pile shell, said mandrel having an inner, tapered, driving member and having an outer, tapered, resilient, split-sleeve member mounted on the driving member; means 45 engaging the driving member for driving the driving member into the sleeve member to radially expand said sleeve member to establish contact throughout the length thereof with the pile shell; said means thereafter also engaging the 50 sleeve member for driving the shell into the ground; means cooperating with the engaging means and the sleeve member and driving member for applying oppositely acting stripping forces to said mandrel sleeve member and said driving 55 member to release engagement of the mandrel with the shell; and said last mentioned means including means for removing said mandrel from said shell.
15. Apparatus for setting piles, including a longitudinally fluted, tapered, tubular shell; a tapered, longitudinally continuous, driving mandrel having an inner, rigid, tapered, driving member and an outer, tapered, split-sleeve, shell 60 expanding member in contact with the bases only of the shell flutes; means for driving the shell into the ground, including a driving head initially contacting with the mandrel driving member to drive the same into the mandrel sleeve member to expand the sleeve member and the shell, and said driving head thereafter contacting also with said mandrel sleeve member to drive the shell into the ground; means cooperating with the driving means and the mandrel for applying an upward pull on said mandrel driving member reacting against said mandrel sleeve member to partially withdraw the driving member from the sleeve member and permit contraction of the sleeve member for releasing engagement thereof with the shell; and said last mentioned means including means for removing the mandrel from the shell.
16. Apparatus for setting piles, including a longitudinally fluted, tapered, tubular shell; a tapered, longitudinally continuous, driving mandrel having an inner, rigid, tapered, driving member and an outer, tapered, expansible and contractable, split-sleeve, shell expanding member in contact with the bases only of the shell flutes; means for driving the mandrel and shell into the ground; means cooperating with the driving means and the mandrel for applying an upward pull on said mandrel driving member reacting against said mandrel sleeve member to partially withdraw the driving member from the sleeve member and permit contraction of the sleeve member for releasing engagement thereof with the shell; and said last mentioned means including means for removing the mandrel from the shell. 10
17. Apparatus for setting piles, including a longitudinally fluted, tapered, tubular shell; a tapered, longitudinally continuous, driving mandrel having an inner, rigid, tapered, driving member and an outer, tapered, expansible and contractable, split-sleeve, shell expanding member in contact with the bases only of the shell flutes; means for driving the shell into the ground, including a driving head initially contacting with the mandrel driving member to drive the same into the mandrel sleeve member to expand the sleeve member and the shell, and said driving head thereafter contacting also with said mandrel sleeve member to drive the shell into the ground; means cooperating with the driving means and the mandrel for applying an upward pull on said mandrel driving member reacting against said mandrel sleeve member to partially withdraw the driving member from the sleeve member and permit contraction of the sleeve member for releasing engagement thereof with the shell; and said last mentioned means including means for removing the mandrel from the shell. 15
18. The method of driving a pile shell, including the steps of utilizing a tapered, radially expansible, tubular, metal shell; utilizing a substantially rigid, tapered, driving mandrel; radially expanding the shell throughout its length by driving and telescopically wedging the mandrel into the shell; then driving the shell and mandrel into the ground; and then removing the mandrel 55 from the shell and leaving the shell in situ in the ground. 50
